UNITED STATES PATENT OFFICE.

EMIL JULIUS BEIN, OF NEWARK, NEW JERSEY, ASSIGNOR TO THE TUCKER FILE COMPANY, OF NEW JERSEY.

CARD-INDEX.

SPECIFICATION forming part of Letters Patent No. 627,967, dated July 4, 1899.

Application filed February 28, 1898. Serial No. 671,876. (No model.)

To all whom it may concern:

Be it known that I, EMIL JULIUS BEIN, a citizen of the United States, residing at Newark, in the county of Essex and State of New Jersey, have invented certain new and useful Improvements in Card-Indexes; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has reference to improvements in that class of cabinets and drawers for card-indexes such as are used in libraries, offices, public buildings, &c.; and my invention has for its several objects to provide an improved means for slidably arranging a card-index holding or supporting block in place on a track in the drawer which will permit of the block being readily moved back and forth on its track or guide within the limit of the length of the drawer or box and also to provide a spring-actuated sliding or adjustably-arranged block which when it binds too firmly against the guide or track plate in the box or drawer on account of a tight fit can be released from such extreme binding arrangement by a slight pressure upon the top of the block to enable it to be adjusted by sliding it on a rod in the said box or drawer.

A further object of this invention is to provide a card-index holding or supporting block slidably arranged on a guide in the box or drawer, the block being of such construction that there will be no forward tilting of the sliding block on its guide or track, as in the constructions now in use, to prevent the placing of the fingers against and in operative engagement with the block when tight against the cards.

A further object of this invention is to provide a novel construction of card-index the mechanism of which shall be effective and simple in its construction and to avoid the awkwardness in manipulating the parts of the device and of having to release a positive clutch, as heretofore; also, to avoid the use of

a perforated track or guide plate and block provided with pins for entering the same, which allows of the clamping of the block at certain intervals only.

The construction of my sliding block and 55 the holding means connected therewith is such that the block is automatically clamped or held in any position on the guide or track plate in which it might have been moved by the operator.

The invention therefore consists in the novel construction of card-index hereinafter set forth and also in such novel arrangements and combinations of the operative elements, such as will be more fully described in the 65 accompanying specification and finally embodied in the clauses of the claim.

The invention is clearly illustrated in the accompanying drawings, in which—

Figure 1 is a perspective view of a card-index embodying the principles of my present invention. Fig. 2 is a top or plan view of one of the boxes or drawers provided with my novel form of card-index holder, and Fig. 3 is a longitudinal vertical section of the same. 75 Fig. 4 is a cross-section of the drawer or box, taken on line α in Fig. 3, when looking in the direction of arrow α' . Fig. 5 is a perspective view of a rod on which the sliding block and index-cards are to be arranged, said view 80 illustrating in connection therewith an escutcheon lock-plate, washer, and spring employed with said rod in my novel construction of card-index. Fig. 6 is a perspective view of the sliding block and its holding or 85 locking means. Fig. 7 is a detail sectional view of a portion of a drawer or box and rod illustrated in said Fig. 5, said rod being provided with a nut for locking or holding it in place in the back of the drawer or box. 90

Similar letters of reference are employed in all of the above-described views to indicate corresponding parts.

In said drawings, A indicates a suitable box or drawer such as is used in the form of cabinet A' represented in Fig. 1; but of course my invention may be used in connection with any other suitable construction of drawer or box.

The drawer A comprises a base a , front a' , back a^2 , and sides a^3 , and the front may be 100

provided with a name-plate, as a^4 , for an index-card.

Secured to the inner face of the front a' of the drawer or box is an upright board b , which 5 has the upwardly-inclining side b' and is provided with a hole or perforation b^2 , as will be clearly evident from Figs. 2 and 3.

The base a of the drawer or box is provided with a pair of longitudinal grooves a^5 , forming 10 a centrally-raised part or ridge a^6 , extending longitudinally from one end of the drawer or box to the other end thereof. Above said part or ridge a^6 I have secured, by means of screws c' or in any other suitable manner, a 15 guide or track plate c , which is of such width that its longitudinal edges partially overhang said grooves a^5 , as will be more clearly evident from an inspection of Fig. 4.

Suitably secured to the face of the front a' 20 of the drawer or box is an escutcheon lock-plate d , which is provided upon the back with a tubular hub d' , adapted to be fitted in a hole formed in said front a' . The front plate of the escutcheon is provided with a hole d^2 25 of a smaller diameter than the inner diameter of the hub portion d' , and d^2 indicates a pair of oppositely-arranged slots or cut-away parts which practically extend to the inner cylindrical surface of the hub d' . The arrangement 30 and size of the opening d^2 are such that a pair of flanges d^4 will be formed contiguous to said slots, as will be clearly seen from Fig. 5. Through this hole or opening d^2 in the plate d and the hole b^2 in the board b is pushed 35 the rear end e' of a rod e , said end e' being loosely fitted and supported in a metal collar or sleeve g in the back a^2 of the box or drawer. Said rod e has a knob e^2 and a flange e^3 and an enlargement e^4 , which is of a slightly smaller 40 diameter than the diameter of the hole or opening d^2 in the plate d , and has a pair of oppositely-extending lugs e^5 , which can be passed through the slots d^3 in said plate d and by a quarter-turn can be brought directly behind the flanges d^4 , as will be clearly understood. Encircling said rod e , directly behind the enlargement e^4 and lugs e^5 , is a washer e^6 , and on said rod, between said washer and the board b , is a coiled spring e^7 , which is 45 pressed by the action of said enlargement e^4 against the washer e^6 when the rod e and said enlargement e^4 are forced through the escutcheon-plate d , and when the rod has been turned and the operator removes his or her 50 hand from the knob e^2 then said spring e^7 acts to force the lugs e^5 against the backs of the flanges d^4 and said rod e is operatively held in place, and the drawer or box may then be pulled out of or pushed into its cabinet by the 55 knob e^2 , as will be evident.

The follower or block f , which is preferably 60 of the shape indicated in Figs. 3 and 6, has an upwardly and backwardly inclining front f^2 and a grooved part f' for the reception of the fingers when it is desired to operate the 65 said block. Said block f has a hole f^3 , whereby it is slidably arranged on said rod e . The

said follower or block f is also movably arranged above the base a of the box or drawer and upon the guide or track plate c by means 70 of a clamping-plate h , which is secured to the bottom of the follower or block f by means of screws h^2 passed through holes in the holding-lugs h' of said plate; but said plate may be otherwise secured to said block, as will be 75 obvious. Said plate h is provided with downwardly and inwardly projecting holding lugs or claws h^3 , which are adapted to extend down into said slots or grooves a^5 in the base a of the box or drawer A and embrace and engage 80 beneath the projecting longitudinal edges of the track-plate c , as illustrated in Fig. 4. Said plate h is provided with suitably-placed openings h^4 and an intermediate bar h^5 , behind which and the face of the base of the block f 85 is held a spring-plate h^6 , having the spring-tongues h^7 projecting through the openings h^4 in the plate h . When the several parts of the block f and its clamping-plate h have been arranged on the rod e and the track-plate c , respectively, it will be evident that the tongues h^7 will bear upon the upper surface of the track-plate c and will force the inwardly-bent portions of the lugs or claws h^3 against the under surfaces of the longitudinal edges of 95 the track-plate c projecting above the grooves in the base a , and thus will operatively hold the block in its upright but slidable position on any part of the track-plate c and the rod e .

The arrangement of the index-cards i , which 100 are of the usual construction and are strung upon the rod e , is clearly indicated in dotted outline in Fig. 3, the cards being held vertically and a sufficient space being provided between the last card and the upwardly-inclining surface of the block f to permit placing the thumb and finger upon the block when tight against the cards and when it is desired to move said block f back upon the rod e and the track-plate c . 110

By the arrangement of the detachable rod and the escutcheon lock-plate d the rod e can be quickly and easily removed for the placing of an index card or cards upon the rod or for the removal of such card or cards from the 115 rod. When it is desired to place the cards on the rod, they are simply placed in position in the drawer or box in front of block f , which is moved up against the last card; the rod is passed through the escutcheon-plate and 120 slipped through the cards, the block f , and into the sleeve g , and then by a quarter-turn of the rod the parts will all be again in their proper positions in the drawer or box A .

As an extra precaution in order to prevent 125 any accidental displacement of the rod e while pulling out the drawer or box A from the cabinet A' , the end e' of the rod e may be provided with a screw-thread, and a suitable thumb-screw or other nut e^8 may be screwed 130 thereon to hold said rod in place, as clearly indicated in Fig. 7.

In order that the fingers may be placed 135 against the back of the block f when it has

been pushed back against the back a^2 of the box or drawer, I have provided said back with an opening a^7 , into which space the fingers are readily inserted to permit the pushing forward of the block f on the track c , as will be clearly evident.

From the above description it will be seen that I have devised a cheap and simply-constructed card-indexing device in which there is no tilting forward of the sliding or adjusting block, as in previous constructions, to prevent the placing of the thumb and fingers upon the block when it is desired to slide the same back on the track-plate, and the awkwardness of having to release a positive clutch, which takes up additional space, is entirely avoided. Owing to the arrangement of the spring-plate on the under surface of the block, the latter can be properly arranged in any desired place upon the track-plate and can be passed back and forth on said plate by a mere pressure of the hand upon the top of the block.

I am aware that changes may be made in the several arrangements and combinations of the parts, as well as in the details of construction thereof, without departing from the scope of my invention. Hence I do not limit myself to the exact arrangements and combinations of the several parts and the construction thereof as described in the accompanying specification and embodied in the claims:

Having thus described my invention, what I claim is—

35 1. In a card-index, the combination, with a drawer or box, of a track-plate in said box or drawer, a block slidably arranged on said track-plate, a clamping-plate secured to the bottom of said block having clamping-lugs in holding engagement with the under side of said track-plate, and a spring on said clamping-plate in frictional sliding engagement with the upper side of said track-plate, substantially as and for the purposes set forth.

45 2. In a card-index, the combination, with a drawer or box, of a track-plate in said box or drawer, a block slidably arranged on said track-plate, and a clamping-plate h attached to the bottom of said block, holding lugs or claws on said plate h in operative engagement with said track-plate, and a spring-plate secured to said track-plate, substantially as and for the purposes set forth.

55 3. In a card-index, the combination, with a drawer or box, of a track-plate in said box or drawer, a block slidably arranged on said track-plate, a spring-actuated clamping-plate secured to the bottom of said block and in frictional holding engagement with said track-

plate, and a guide-rod removably arranged in said drawer and passing through a hole in said block, substantially as and for the purposes set forth.

65

4. In a card-index, the combination, with a drawer or box, of a track-plate in said box or drawer, a block slidably arranged on said track-plate, a spring-actuated clamping-plate secured to the bottom of said block, and in frictional holding engagement with said track-plate, a collar g in the back of said drawer or box, an escutcheon-plate d in the front of said drawer or box, having a tubular hub d' and said plate d having an opening d^2 and slots d^3 and a flange d^4 , a spring-actuated guide-rod removably arranged in said collar g and said escutcheon-plate, and lugs on said guide-rod adapted to be turned in holding engagement with said flange d^4 , and said rod passing through a hole in said block, substantially as and for the purposes set forth.

70

5. In a card-index, the combination, with a drawer or box, of a track-plate in said box or drawer, a block slidably arranged on said track-plate, a clamping-plate h attached to the bottom of said block, holding lugs or claws on said plate h in operative engagement with said track-plate, a spring-plate secured to said plate h having spring-tongues in frictional sliding engagement with said track-plate, and a guide-rod removably arranged in said drawer or box and passing through a hole in said block, substantially as and for the purposes set forth.

80

6. In a card-index, the combination, with a drawer or box, of a track-plate in said box or drawer, a block slidably arranged on said track-plate, a clamping-plate h attached to the bottom of said block, holding lugs or claws on said plate h in operative engagement with said track-plate, a spring-plate secured to said plate h having spring-tongues in frictional sliding engagement with said track-plate, a collar g in the back of said drawer or box, an escutcheon-plate d in the front of said drawer, having a tubular hub d' and said plate d having an opening d^2 , slots d^3 and a flange d^4 , a spring-actuated guide-rod removably arranged in said collar g and said escutcheon-plate, and lugs on said guide-rod adapted to be turned in holding engagement with said flange d^4 , and said rod passing through a hole in said block, substantially as and for the purposes set forth.

90

7. In testimony that I claim the invention set forth above I have hereunto set my hand this 21st day of February, 1898.

EMIL JULIUS BEIN.
